UNITED STATES PATENT OFFICE.

WILLIAM M. SCHLESINGER SELWYN, OF PHILADELPHIA, PENNSYLVANIA.

LOCK.

SPECIFICATION forming part of Letters Patent No. 592,835, dated November 2, 1897.

Application filed September 5, 1896. Serial No. 604,973. (No model.)

To all whom it may concern:

Be it known that I, WILLIAM M. SCHLESINGER SELWYN, a subject of the Queen of Great Britain, residing at Philadelphia, in the county of Philadelphia and State of Pennsylvania, have invented certain new and useful Improvements in Locks; and I do hereby declare the following to be a full, clear, and exact description of the invention, such as will enable others skilled in the art to which it appertains to make and use the same.

My invention has relation to improvements in locks, with special reference to such locks on and about receptacles for the temporary reception and keeping of articles of value, and has for its object as well the avoidance of the complication and delay incident to the use of a combination-lock as the provision of greater safety where a number of persons use such a receptacle successively. These are obtained, first, by the provision of a lock having changeable locking adjustments; second, by means whereby the adjustment of the lock is changed upon its successive use, and, third, by the furnishing to the user another and different key upon its successive use, such key being the only one which will unlock the lock for the time being. I obtain these objects by the mechanism illustrated in the accompanying drawings, in which—

Figure 1 is a top view of the lock. Fig. 2 is a vertical section. Fig. 3 is a cross-section on line 1 2, Fig. 2. Figs. 4 and 5 are top views of the tumblers of the lock in different positions. Fig. 6 is an end view of part of the tumblers in the position shown in Fig. 5. Fig. 7 is a vertical section of the lock on line 3 4, Fig. 1. Fig. 8 is a cross-section on line 5 6, Fig. 2. Fig. 9 is a cross-section on line 7 8, Fig. 2. Fig. 10 is a partial view of the magazine with its keys. Fig. 11 is a partial view of the interior surface of the casing surrounding the magazine. Fig. 12 is top view of a portion of the locking-bolt of the lock and of the plate controlling its motion. Fig. 13 is a side view of the parts shown in Fig. 12. Fig. 14 is a section of the plate shown in Figs. 12 and 13. Fig. 15 is a side view of the catch controlling the motion of the magazine. Fig. 16 is a top view of the catch, and Figs. 17 and 18 are views of two keys used in the lock.

Similar letters and figures refer to similar parts throughout the several views.

The lock consists of a casing A, attached to plate B and containing the cylinder or magazine C. This cylinder is provided with a number of slots, (marked 1 2 3 4, &c., up to 28.) Each slot is normally provided with two keys, as shown in Fig. 10, the keys being held apart and in proper position on the cylinder by means of the spiral groove a, Fig. 11, cut in the inner surface of casing A. Through cylinder C and plate B passes bolt D, Fig. 2, provided at one end with nut E and at the other end with plate d. Portion d' of bolt D is of larger diameter than the part that passes through cylinder C and is provided with teeth, as shown more clearly in Fig. 8. These teeth engage with teeth of the planet-wheel F. The teeth of the latter also mesh with the teeth of the stationary segment G, which is fastened to the casing A. Planet-wheel F is provided with a short centrally-located shaft f, which engages with the fork H, the latter being loosely pivoted on bolt D. Fork H is provided with a radial slot, Figs. 2 and 8, in which moves catch h. Spring h' presses this catch outwardly and causes it to engage with the ratchet-teeth c of cylinder C. On turning, therefore, bolt D in the direction indicated by the arrow in Fig. 8 the planet-wheel F will be moved in the same direction, and carries the fork H with it. On account of the inclination of the ratchet-teeth c cylinder C will not be affected by the motion in this direction. On, however, reversing the motion of the bolt D the planet-wheel F will also travel in the opposite direction to that indicated by the arrow, and will carry along with it fork H and also cylinder C. Although, therefore, the motion of H will be an oscillating one, cylinder C will rotate in one direction only. To further insure cylinder C from traveling in any direction but the desired one, catch T, Fig. 8, engaging with one of the slots of cylinder C, is provided. Handle I is attached to bolt D in such a manner that it can be moved from the position shown in Fig. 2 in full lines to that shown in the same figure in dotted lines. When in the former position lug i of handle I passes through slots in plates d, B, and K, so that on

- turning the handle I around the central line of D, as axis, it carries along with it bolt D and plate K, the latter being loosely pivoted on bolt D. The motion of I is limited by the slot b in plate B. This slot b is only at one place (corresponding to the locked position of the lock) wide enough to allow lug i to enter it, and i is provided with a recess (shown at i', Fig. 2) which allows it to be moved in slot b and prevents its being pulled out, except when in the position above indicated. Bolt D imparts its motion, as already described, by means of the sun-and-planet transmission to fork H, and intermittently to the cylinder or magazine C. The latter is, however, prevented from turning in either direction until catch T is partially released by lug i of handle I on the latter completing its motion in the direction of the arrow in Figs. 1 and 8, which corresponds to the motion for unlocking the lock. This is accomplished by providing catch T with a beveled surface t, Figs. 15 and 16, in the path of lug i, so that when the latter has come to the end of its stroke in this direction it will have moved catch T sufficiently outward to allow cylinder C to be moved in the desired direction on the return stroke of I, but the longer face of catch T—i. e., the face marked t'—still prevents the cylinder C from moving in the opposite direction.
- The length of slot b and the sun-and-planet transmission are so arranged that each time the handle I is turned, first in one direction for unlocking the lock and then in the other direction for locking the lock, a new slot of cylinder or magazine C, with its corresponding keys, is brought opposite to the openings a', a², and a³ in casing A.
- Plate K is provided with teeth, as shown in Fig. 12, which engage with corresponding teeth of the locking-bolt L, so that as K is moved backward and forward by handle I it will move L into locking or unlocking position. Attached to L by means of bolt l are a number of fork-shaped tumblers M', M², M³, M⁴, M⁵, and M⁶. (Shown in Figs. 4 and 5.) These tumblers are pressed in against casing A by means of springs m', m², m³, m⁴, m⁵, and m⁶. They are also provided with lugs e, which pass across opening a' in casing A as the bolt L is moved forward into unlocking position. Should there now be a key in the slot of cylinder C opposite the opening a', the slots in this key will allow part of the tumblers M to drop in, or, in other words, to move closer toward cylinder C, whereas the lugs on the key will hold the rest of the tumblers in their original position, as shown in Figs. 5 and 6.
- When in the position shown in these figures—that is, after handle I has been moved a small part of the distance it has to move to unlock the lock—tumblers M', M², M³, M⁴, M⁵, and M⁶ encounter fingers n', n², n³, n⁴, n⁵, and n⁶ of the opposing tumblers N', N², N³, N⁴, N⁵, and N⁶, and if these fingers are in positions corresponding to those of tumblers M they will en-

ter between the jaws of the latter. Should, however, one of the fingers n not be in the proper position corresponding to that of its opposing tumbler M, it will strike against one or the other of the prongs of this tumbler instead of passing between them, and thus arrest the further motion of the locking-bolt L. Tumblers N', N², N³, N⁴, N⁵, and N⁶ are made U-shaped, as shown in Fig. 7, one end forming the already-mentioned fingers n and the other end being provided with lugs e'. These tumblers are pivoted on bolt O in such a manner that their lugs e' are opposite the opening a² of casing A, and the lugs are pressed into this opening and against the key opposite it by means of springs s', s², s³, s⁴, s⁵, and s⁶. When the lock is turned from its unlocked to its locked position by turning the handle I into the position shown in Figs. 1 and 2, bolt D turns the cylinder or magazine C, as described above, so that a new slot (slot 1) is brought into operative position opposite openings a', a², and a³ of casing A. One of the two keys in this slot 1—that is, key 1'—will be opposite opening a², and the springs s will cause the tumblers N to move into positions corresponding to the slots and lugs of this key, as shown in Figs. 2 and 9. Key 1² will come opposite opening a³ in casing A and will fall through this opening into the drawer P, as shown in Fig. 2. By pulling out this drawer the key can be removed by the user of the lock. When the lock is in its locked position, the slots in plates d and K and the enlarged part of slot b in plate B coincide with slot 1 of cylinder or magazine C, so that i can be withdrawn from these slots by turning the handle I into the position shown in dotted lines in Fig. 2.

To again unlock the lock, key 1² is placed into the slot in plate d and is pressed home into slot 1 of cylinder or magazine C by bringing the handle I back into the position shown in full lines in Fig. 2. Key 1², which before was underneath key 1', will now be above it and opposite opening a'. On now turning handle I to unlock the lock bolt L will carry along with it tumblers M, moving them against fingers n of tumblers N; but before encountering these the lugs e of tumblers M will have engaged with key 1² and the tumblers M will be set in such a position that the fingers n can enter between the jaws of the corresponding tumblers M, as shown in Fig. 5, and the motion for unlocking can be completed.

On again locking the lock, slot 2 of cylinder or magazine C is brought into operative position, and tumblers M, moving back with bolt L, will again be in the position shown in Fig. 4. Key 2² is now opposite opening a², setting tumblers N in a new position. Key 2² falls through opening a³ into the drawer P, from where it is again removed by the user of the lock and placed into the slot in d for the purpose of unlocking the lock. In this manner each of the twenty-eight slots of the cylinder or

magazine C, with its respective keys, is brought successively into operating position. On using the lock the twenty-ninth time slot 1 is again brought into position opposite the openings a' , a^2 , and a^3 , but on account of spiral groove a in casing A key 1², which on unlocking the lock the first time was opposite opening a' , is now opposite opening a^2 , and key 1' is now opposite a^3 and falls into the drawer P. The lock may therefore be used another twenty-eight times, or altogether fifty-six times, before the same key is again fed to the user.

It is evident now that should any but the right key be placed in the lock the latter will not unlock, as unless this key sets all of the tumblers M in the proper position to allow the corresponding fingers n of tumblers N to pass between the jaws of the former the unlocking motion of the bolt L will be arrested. To avoid the possibility of any unauthorized person trying to open the lock by trying a number of keys in it, one after the other, until the right one is discovered, plate K may be provided with catch R, Figs. 12 and 14, which moves in groove S of cylinder C, Figs. 2 and 8. On turning the handle to unlock the lock this catch will readily pass over and beyond the key placed in the lock before tumblers M encounter fingers n . As, however, if the key be not the proper one, the motion will then be arrested before the lock is unlocked and before catch h of fork H has engaged with another ratchet-tooth of cylinder C, the latter will not be moved by turning the handle I back again, and catch R will therefore engage with the key placed in the lock and arrest the motion of I in this direction also, as catch T, Fig. 8, prevents cylinder C from turning, I not having been able to complete its full stroke and release this catch. The handle I will therefore be placed in a position in which it can neither move forward nor backward nor be pulled out of the slot in the plate d to uncover the latter, as it cannot reach the end of its stroke to the place where the wider part of slot b in plate B will admit its removal.

To be mates the keys in the same slot of cylinder or magazine C must be so arranged that if the key opposite opening a' has, for example, a slot near its upper part to engage with tumbler M' the key opposite opening a^3 must have a slot near its lower part to engage with tumbler N' and set finger n' to correspond with the position of tumbler M'. This latter key when dropped into the slot to come opposite opening a' would therefore engage with tumbler M⁶, whereas its mate engaged with tumbler M'. To insure the keys being dropped into the slot of plate d in the proper position, they are provided with grooves, as shown in Figs. 17 and 18, and the slot in plate K is provided with corresponding lugs, as shown at k, Fig. 12.

When the lock is unlocked, drawer P cannot be pulled out, as the locking-bolt L passes through the recess p of the drawer.

Only when the lock is locked can drawer P be pulled out, as in that position recess l' in bolt L will permit its passage. Lug p' prevents the drawer P from being entirely withdrawn from the lock.

By providing the lock with a larger or less number of tumblers any number of keys can be provided for the lock, each key being different from any of the rest, and by providing a corresponding number of slots in the cylinder or magazine C the lock can be made to be used any desired number of times before the first key used in unlocking it is fed out of the lock again. It is obvious that the lock can be used indefinitely, as each key that has been removed from it has to be returned for the purpose of unlocking the lock, and therefore takes its proper position in the magazine.

What I claim as my invention, and desire to secure by Letters Patent, is—

1. In a lock, in combination with two separate and independent keys, provided with suitable projections or indentations, tumblers 90 engaging with the projections or indentations, and mechanism whereby the simultaneous use of both keys is required to unlock the lock, substantially as described.

2. In a lock, the combination of two or 95 more keys normally stored in the lock, and mechanism whereby, on operating the lock, one of the keys is fed to the user of the same, substantially as described.

3. In a lock, the combination of two or 100 more keys normally stored in the lock, mechanism whereby the simultaneous use of two of the keys is required to unlock the lock, and mechanism whereby, on operating the lock, one of the keys is fed to the user of the 105 same, substantially as described.

4. In a lock, in combination with two or more keys normally stored in the lock, mechanism for feeding one of the keys to the user of the lock and for placing another key into 110 operating position in the lock, and mechanism whereby the simultaneous use of both these keys is required to unlock the lock, substantially as described.

5. In a lock, in combination with two or 115 more keys normally stored in the lock, mechanism whereby on the successive use of the lock another and different key is fed to the user of the same, and another and different key is placed into operative position in the lock, 120 and mechanism whereby the simultaneous use of both keys is required to unlock the lock, substantially as described.

6. In a lock, in combination with two or more keys normally stored in the lock, mechanism whereby on its successive use another and different key is fed to the user of the same, and another and different key is placed into operative position in the lock, mechanism whereby the simultaneous operation of 130 both keys is required to unlock the lock, and means for automatically removing the previously-used keys out of operative position, substantially as described.

7. In a lock, in combination with two or more keys normally stored in the lock, mechanism for feeding one of the keys to the user of the lock and for placing another one of the 5 keys into operative position in the lock; mechanism whereby the simultaneous operation of both these keys is required to unlock the lock; a slot for the reception of the key fed to the user, and means for preventing the 10 removal of the key from the slot, after the motion to unlock the lock has once been commenced, for the purpose specified.
8. In a lock, the combination with a lock-

ing-bolt of two sets of tumblers located in such a manner that on unlocking the lock 15 they engage with each other, and a separate key for each set of tumblers, the simultaneous operation of both keys being required to set the tumblers in position to allow the lock to be unlocked, substantially as described. 20

In testimony whereof I affix my signature in the presence of two witnesses.

WILLIAM M. SCHLESINGER SELWYN.
